UNITED STATES PATENT OFFICE.

JOHN M. HUTCHINS, OF OKLAHOMA, OKLAHOMA, ASSIGNOR OF ONE-HALF TO PATRICK J. MADIGAN, OF OKLAHOMA, OKLAHOMA.

MEANS FOR THROWING SWITCHES.

1,186,790.

Specification of Letters Patent. Patented June 13, 1916.

Application filed January 31, 1916. Serial No. 75,272.

To all whom it may concern:

Be it known that I, JOHN M. HUTCHINS, a citizen of the United States, residing at Oklahoma, in the county of Oklahoma and State of Oklahoma, have invented certain new and useful Improvements in Means and Throwing Switches, of which the following is a specification, reference being had to the accompanying drawings.

10 An object of the invention is to provide a more convenient means for throwing switches in rail-way tracks.

Other objects and advantages of the invention will be set forth in the ensuing description.

The accompanying drawings show one embodiment of the invention in practical form.

Figure 1 is a right-hand side elevation of 20 the front end of a street car and a portion of track, with the improvements applied thereto. Fig. 2 is a plan view, partly in section, of the parts shown in Fig. 1. Fig. 3 is an enlarged view in the same direction 25 as Fig. 1, showing an assemblage of some of the parts. Fig. 4 is a still larger plan view of a valve mechanism which is shown at the point indicated by the arrow 4 in Fig. 3. Fig. 5 is a sectional view taken on 30 the line 5—5 of Fig. 4. Fig. 6 is a sectional view on the same scale as Figs. 4 and 5, taken on the line 6—6 of Fig. 3. Fig. 7 is an elevation view of a valve, taken in 35 the same direction as Fig. 3.

Referring to the several figures, in all of 40 which like characters of reference designate like parts, the inventor provides a tapered tool 10 adapted to be forced down between a main rail 11 and a switch-tongue 12 to "split" said rail and switch-tongue apart, and provides improved means for supporting this tool and controlling its movements. In providing this supporting and controlling means, a pressure cylinder 45 13 is arranged in vertical position and carried by a supporting crane 14 which is pivoted to the front of the car body 15 on a vertical axis. This crane 14 may comprise a vertical pivot-shaft 16 which is journaled 50 in suitable bearings 17 and 18 on the car body 15, and brace-arms 19, 20, and 21 which project forward and connect said pivot-shaft and the cylinder 13 into a rigid supporting frame.

55 A long piston 22 is fitted in the cylinder

13 and projects out the lower end thereof, the extreme lower end of this piston carrying the splitting tool 10; and this piston is held normally upward out of operative position by a tension spring 23 which is 60 hitched at the top of the interior of said cylinder and at the bottom of the bore 24 of the tubular upper end of said piston. Means later described are provided for forcing the piston 22 downward at will. 65 In further arrangement, means are provided for swinging the crane 14 from one side of the track to the other. In providing this means, a second pressure cylinder 25 is secured to the under side of the car platform 70 26 and provided with a piston of well known construction which does not show in the drawings, the rod 27 of this piston passing out the end of said cylinder and terminating in a toothed rack 28 which is in permanent mesh with a gear-segment 29 on the lower end of the pivot-shaft 16. By admitting compressed air to one end of the cylinder 25 or the other, the action of the piston rod 27 on the gear-segment 31 of the 75 pivot-shaft 16 will enable the car driver to swing the crane 14 to the desired position for operation of the tool 10. Compressed air for moving the piston in the cylinder 25 may be taken from the train-pipe 30, which is a 80 well known part of the brake equipment of modern cars; and to enable the car driver to control said air a valve mechanism 31 is supported by a bracket 32 from the lower side of the car platform 26. As best shown 85 in Fig. 6, this valve mechanism 31 comprises a valve-casing 33 in which is a rotatable valve 34. This valve 34 is of well known construction and arrangement and is so ported that by its manipulation the air supplied 90 from the train-pipe 30 to the valve-casing 33 through the pipe 35 may be alternately directed to the ends of the cylinder 25 through the two pipes 36 and 37, the cylinder exhausting through a port 38 of said 95 valve-casing. To move the valve 34, it is provided with a stem 39 which extends up into the driver's compartment of the car and is provided with a handle 40; the upper end of this stem being journaled in a suitable supporting bracket 41.

In arranging to force the piston 22 and tool 10 downward, the stem 39 of the valve 34 is made tubular and is supplied with air through a small port 42 in said valve. The 110

upper end of the stem 39 terminates in a valve-casing 43 which is fitted with a valve 44, best shown in Figs. 4 and 5; the handle 40 which is swung in a horizontal plane to move the lower valve 34 being attached to the valve 44 and adapted to be swung in a vertical plane to move the latter valve. A flexible pipe 45, leads from the valve-casing 43 to the upper arm 21 of the crane 14, and said arm is made tubular from the joining end of said pipe 45 on down to the bore 46 of the cylinder 13. The valve 44 is of well known construction and arrangement, and so ported that when the handle 40 is swung downward the air from the stem 39 is directed into the upper end of the cylinder 13 to drive the piston 22 and tool 10 downward; and when the handle 40 is raised back to normal position the air exhausts out through a port 47 of the valve-casing 43 and allows the spring 23 to raise the piston 22 and tool 10 back up to normal position.

In manipulating the valve 34 by swinging the handle 40 in a horizontal plane, the car driver may swing the crane 14 to bring the tool 10 over one rail 11 or the other with the same ease and accuracy that he could if the handle were attached directly to the pivot-shaft 16; and after bringing the cylinder 13 to the right place, the swinging of the handle 40 downward to move the valve 44 is the natural movement of said handle to force the piston 22 and tool 10 downward to throw the switch.

To protect the piston 22 from injury in case the tool 10 becomes wedged or caught in the track before the car is fully stopped, the tool is yieldably connected to the piston 40 and adapted to swing backward when caught.

In arranging the yieldable connection of the tool 10, the lower end of the piston 22 is flanged outward, as at 48, thus forming a wide base against which the widely flanged upper end 49 of the tool is normally seated.

A strong tension spring 50 in the bore 51 of the tubular lower end of the piston 22 holds the tool 10 upward in seating contact with said piston and allows said tool to yield when resisted by an obstruction or caught in the track, a substantially cone-shaped centering-pin 52 on the upper end of the tool engaging the bore of the piston 55 to hold the upper part of said tool against lateral displacement.

Having thus described the invention, I claim:—

1. In combination with a car, a tool carried by the car and adapted to be thrust

downward to split track rails, and means carried by the car for moving the tool from one track rail to the other.

2. In combination with a car, a supporting crane pivoted to the car and adapted to swing on a vertical axis, a tool carried by the crane and adapted to be thrust downward to split track rails, and means carried by the car for thrusting said tool downward.

3. In combination with a car, a supporting crane pivoted to the car on a vertical axis, means operable by compressed air for swinging said crane, a tool carried by the crane and adapted to act on track rails, and means operable by compressed air for causing said tool to act.

4. In combination with a car, a pressure cylinder carried by the car and having a piston, a tool carried by the piston to act on a track rail, the connection between the piston and tool being yieldable, and means for supplying compressed air to the cylinder.

5. In combination with a car, a supporting crane pivoted to the car on a vertical axis, a vertical pressure cylinder carried by the crane and having a piston, a tool carried by the piston to act on a track rail, means for supplying compressed air to the cylinder to force the tool to act, and yieldable means in the cylinder for drawing the tool away from the rail when the air pressure is removed.

6. In combination with a car, a crane carried by the car and pivoted thereto on a vertical axis, a cylinder carried by the crane and having a piston, a tool carried by the piston to act on a track rail, a gear segment operatively engaged with the crane, a second cylinder carried by the car and having a piston rod, said rod having rack-and-pin engagement with the gear segment of the crane, a valve arranged to control a supply of compressed air to the second cylinder and having a stem, said stem carrying a second valve adapted to control a supply of air to the first-named cylinder, said second valve having a handle by which it may be moved to direct the air to the first-named cylinder and by which the stem carrying said second valve may be operated to move the valve which directs the air to the second cylinder, and a source of compressed air to supply said cylinders.

Witness my hand this 22d day of January, 1916.

JOHN M. HUTCHINS.
